United States Patent Office

Des. 205,129
Patented June 28, 1966

205,129

DOORSTOP

Isabelle M. Glass, 1223 Drake Drive, Simi, Calif.

Filed June 17, 1965, Ser. No. 85,777

Term of patent 14 years

(Cl. D10—5)

FIG. 1

FIG. 2

FIG. 3

I claim:

The ornamental design for a doorstop, substantially as shown.
